UNITED STATES PATENT OFFICE

2,500,622

ADJUSTABLE STUMP SUPPORT FOR
ARTIFICIAL LEGSJohn Aho, Brooklyn, N. Y., assignor of one-half
to Herman Niessen, Brooklyn, N. Y.

Application May 10, 1946, Serial No. 668,734

13 Claims. (Cl. 3—9)

1

This invention relates to improvements in artificial limbs, and particularly to an improved artificial leg having a knee and foot member.

An object of the present invention is to provide an artificial leg which is comfortable to the wearer, adjustable in position around the live leg stump, and permits lateral movement for different sizes of leg stumps.

Another object is to provide an improved artificial leg having an adjustable stump socket made up of a plurality of weight or stump supports with adjustable links therebetween.

A further object is to provide an artificial leg having a plurality of spaced weight supports or carriers which are interlinked with ball and socket adjustment members to thereby permit individual or total lateral adjustment of the weight supports.

Other objects will appear from a reading of the following description of the invention, taken in conjunction with drawings, wherein:

Fig. 1 is a perspective view of the inner sleeve or liner of the stump socket of the invention showing the knee pad windows;

Fig. 2 is a perspective view of the shell portion of the stump socket, which surrounds the inner sleeve or liner of Fig. 1. The sleeve of Fig. 1 is designed to fit within the shell portion of Fig. 2;

Fig. 3 is a top plan view of the artificial leg of the invention with the sleeve of Fig. 1 nesting within the shell of Fig. 2;

Fig. 4 is a horizontal cross-section taken on line 4—4 of Fig. 2;

Fig. 5 is an enlarged top plan fragmental view of Fig. 3 shown partly in elevation and partly in section;

Fig. 6 is a vertical cross-section taken on line 6—6 of Fig. 5;

Fig. 7 is a plan section of a modified form of weight support or carrier;

Fig. 8 is a horizontal cross-section taken on line 8—8 of Fig. 7;

Fig. 9 is a front elevation of a modified form of link adjustment looking from the inside of the shell portion of the stump socket;

Fig. 10 is a vertical cross-section taken on line 10—10 of Fig. 9; and

Fig. 11 is a vertical cross-section taken on line 11—11 of Fig. 9.

Throughout the figures of the drawing, the

2

same parts are designated by the same reference characters.

Referring to Figs. 1 through 6 in more detail, the artificial leg of the invention comprises a hollow leg member 10, usually of wood, which extends from the lower foot member, not shown, to the stump socket comprising an inner sleeve or liner 12 (Fig. 1) and a surrounding main or shell portion 14 (Fig. 2).

The shell or main portion of the stump socket includes a knee cap part 16 to which is fastened a knee weight support or carrier 18, two side weight supports or carriers 20 and 22, and a rear pivot support plate 24. It should be noted that the three weight supports or carriers 18, 20 and 22 have weight bearing surfaces which are formed to fit those areas of the live leg stump, not shown, which they touch. The weight supports 18, 20 and 22 and the rear plate 24 are interlinked by adjustable links in a manner described later.

The sleeve or liner 12 is provided with three windows 30 which register with the three weight supports when the sleeve 12 is inserted into the shell portion 14. These windows are sufficiently large to enable the pads of the weight supports to pass therethrough. The solid portions of the sleeve 12, located between the windows, prevent the adjustable links and the rear pivot support plate 24 from touching the live leg stump adapted to enter sleeve 12, and also as a sheath support for the live leg stump, aiding in maintaining the position of the leg on the weight carriers of the stump socket.

The weight or stump supports are attached to the shell of the stump socket by means of a ball and socket arrangement (note Figs. 5 and 6) comprising a pair of balls 1 and 2 which enter into sockets 3 and 4 respectively. A locking screw 5 (Fig. 6) serves to lock the ball 1 to the ball 2. Rubber cushions 6 prevent the balls from rattling within their respective sockets.

Each weight support comprises a pad of suitable material having turned-in ends 7 which overlap a pad backing plate 9. This plate 9 and the turned-in ends 7 rest against a plate 11 which is an extension of the hollow socket 3. It should be noted that within the sockets 3 and 4 there are provided steel shells 13 against 50 which ride the balls 1 and 2 and the rubber

cushions 6. The main hollow leg member 10 is secured or fastened to the stump socket shell by means of rivets 15. A plate 17 forms an extension of the hollow socket 4 and is sandwiched between the stump socket shell and an outer plate 19 by means of rivets 91.

The weight supports or carriers 18, 20 and 22 are linked to each other and attached to the rear plate 24 by means of adjustable links 26 and 28. Each link includes a ball and socket construction and an adjustable band or turn-buckle. Thus, referring to Fig. 5, the links 26 and 28 have at each end a ball 21 which fits into a socket 23 at the rear of the weight support. The sockets 23 are supported by the weight supports or carriers at both side edges. Within each socket 23 there is provided a steel shell 25. A restraining clip 27 which is fastened to the pad backing plate by a rivet 29 serves to restrain the balls 21 of the links 26 and 28 from leaving their respective sockets 23.

Each adjustable link 26 and 28 is provided with lock nuts 70 at both ends for locking the link in position, thus preventing undesired change in adjustment during use.

The main portion of shell 14 is provided with four apertures or windows 32 which register with the adjustable portions of the links or turn-buckles 26, 28 for enabling adjustment of the links from the outside of the artificial limb.

The top part 49 of the stump socket shell 14 of the stump socket is also provided with screw holes 31. These holes 31 register with screw holes 31' on the upper flange portion 34 of the inner sleeve or liner 12 and enable both of these portions of the stump socket to be fastened securely together by screws, not shown, which enter these holes.

Fig. 4 shows the details of the rear pivot support 24. This support comprises a plate 24 which is fastened to the stump socket shell by means of rivets 41. Attached to the plate 41 by these same rivets is a hollow socket 43 which accommodates in its interior the adjacent balls 21 of the adjustable links 28. Positioned between the flat end portions of balls 21 in the interior of socket 43 is a rubber cushion 44 for preventing rattling.

Among the advantages of the artificial limb of the invention are: The weight supports or carriers automatically adjust themselves to the movement of the knee of the wearer due to the ball and socket or swivel connections between the weight supports and the stump socket shell; the adjustable links between weight supports or carriers and rear pivot support enable individual or total lateral adjustment of the weight supports around the live leg stump; the adjustable links are covered by the inner sleeve and cannot touch or irritate the wearer; and the entire construction provides a feeling of comfort and ease of operation approaching that of the natural leg and foot.

Figs. 7 and 8 illustrate, by way of example only, an alternative swivel construction for the ball and socket arrangement of Fig. 6. In Figs. 7 and 8, the pad or weight carrier is designated 50, the pad backing plate 51 and the socket plate 52. The stump socket shell is designated 53. The swivel construction between the weight carrier 50 and the stump socket shell 53 includes a pair of hinge plates 54, a pair of hinge pins 55, a pair of hinge swivel plates 56, and a swivel 57.

In the operation of Figures 7 and 8, the shell 53 is stationary or fixed. The pin 55 immediately adjacent the shell 53 permits a vertical pivoting

or swiveling action and acts as a hinge pin enabling movement of the combination of weight carrier 50 and plates 56 and 57 around this particular pin. The other pin 55 immediately adjacent the weight carrier 50 also acts as a hinge pin but of a more restricted nature and permits movement of the weight carrier 50 relative to the swivel construction plates 56. Thus the weight carrier 50 can adjust itself vertically in accordance with the changing requirements of the leg stump in its movement.

That portion of the hinge plate 54 which is within the socket plate 52 is a circular disc and rides within a correspondingly shaped circular portion of 52, and permits movement of the unit 50, 51 and 52 in the plane of disc 54.

Swivels 57 are able to move within plates 56 in a plane parallel to the swivels 57, as shown in Figure 7. Essentially, the swivels 57 and their surrounding enclosing plates 56 act as a restricted ball and socket which enables movement in a single plane.

From the foregoing it will be clear that the construction of Figures 7 and 8 permits a universal movement analogous to the ball and socket construction of Figure 6.

Figs. 9, 10 and 11 illustrate a modified form of link adjustment mechanism as seen from the inside of stump socket 14 with the inner sleeve removed. This modified construction includes an adjustment band 60, in effect, a rear plate rigidly held in a socket by ball 61, and a front channel-shaped member 62. The ball 61 is located in the same place as balls 21 of Figures 4 and 5. Member 62 is also rigidly held in a socket by a ball, not shown, fastened to the right hand end of this member. The member 62 is provided with a rack 63 in association with a gear 64. Front member 62 is also provided with a slot S in which rests a tab or tongue T forming part of the rear plate or band 60. Tab T protrudes into slot S and serves as a guide to maintain relative alignment of both members 60 and 62.

In order to adjust the linkage of Figs. 9, 10 and 11, the gear 64 is turned by means of a slotted head H, thus moving members 60 and 62 relative to each other and tightening or loosening the linkage.

A key slot K is provided for tightening the front lock screw 65 provided with a gear, as shown.

Another important advantage of the invention is that the artificial leg eliminates the need for a temporary artificial leg in the interval of time after the amputation and before the fitting of the permanent artificial limb. Since the amputated limb shrinks in size for some period of time after an artificial leg is first used, it has been customary, heretofore, to provide a temporary artificial leg. The artificial leg of the invention, however, due to its various adjustable features may be used both as the temporary and permanent leg, thus eliminating the need for more than one artificial limb and the consequent expense.

A further advantage of the invention is that the various elements may easily be replaced due to wear and tear, without the necessity of replacing the entire limb as heretofore required.

The principles of the invention insofar as the pivotal or swiveled weight supports or carriers, and adjustable links are concerned, are applicable to different types of artificial limbs, as for example, a leg for use with live stumps amputated above the knee, and for this reason the in-

vention is not limited to a leg having a knee and foot member.

I claim:

1. A socket for an artificial limb, comprising a shell, a plurality of spaced stump supports arranged on the interior of said shell adapted to receive therein the stump of an amputated limb, individual ball and socket connections between said stump supports and said shell, and ball and socket links interconnecting said stump supports.

2. A socket for an artificial limb, comprising a shell, a plurality of spaced stump supports arranged on the interior of said shell adapted to receive therein the stump of an amputated limb, individual ball and socket connections between said stump supports and said shell, and ball and socket links interconnecting said stump supports, said links being adjustable in length.

3. A socket for an artificial limb, comprising a shell, a plurality of substantially circumferentially spaced stump supports arranged on the interior of said shell adapted to receive therein the stump of an amputated limb, individual connections between said stump supports and said shell, said connections being so constructed and arranged as to permit pivotal movement of said stump supports, a single link of adjustable length between each two adjacent stump supports and having ends which are secured to and terminate at said supports.

4. A socket for an artificial limb, comprising a shell, a plurality of substantially circumferentially spaced stump supports arranged on the interior of said shell adapted to receive therein the stump of an amputated limb, individual connections between said stump supports and said shell, said connections being so constructed and arranged as to permit movement of said stump supports in at least one plane, and links of adjustable length between said stump supports, said shell having windows or openings at the locations of said links for enabling adjustment of said links from the outside of said shell.

5. A socket for an artificial limb, comprising a shell, a plurality of spaced stump supports arranged on the interior of said shell adapted to receive therein the stump of an amputated limb, individual ball and socket connections between said stump supports and said shell, and ball and socket links interconnecting said stump supports, said links being adjustable and of the turn-buckle type, said shell having openings at the locations of said turn-buckles for enabling adjustment of said links from the outside of said shell.

6. A socket for an artificial limb, comprising a shell, a plurality of substantially circumferentially spaced stump supports arranged on the interior of said shell adapted to receive therein the stump of an amputated limb, individual connections between said stump support and said shell, said connections being so constructed and arranged as to permit movement of said stump support in at least one plane, and links of adjustable length between said stump supports, and an inner sleeve fitting into said shell, said sleeve having windows for enabling the stump supports to pass therethrough for engaging the stump of the amputated limb, those portions of the inner sleeve between said windows covering said links and preventing said links from touching the stump.

7. A socket for an artificial limb, comprising a shell adapted to receive therein the stump of

an artificial limb, a plurality of non-overlapping and substantially circumferentially spaced padded stump supports on the interior of said shell, links between said supports and independently adjustable of each other, and an inner sleeve for said shell, said sleeve preventing said links but not said pads from touching the stump of the artificial limb.

8. A socket for an artificial leg having a knee and a foot member, comprising a shell adapted to receive therein the stump of a leg amputated below the knee, a stump support at the front or knee part of said shell, stump supports at the sides of said shell, a rear support fixedly fastened to said shell, said supports being substantially circumferentially spaced on the interior of said shell, individual ball and socket connections between said shell and said front and side stump supports, adjustable links between said shell and said front and side stump supports, adjustable links between said front stump support and said side stump supports, and links between said side stump supports and said rear support.

9. A socket for an artificial leg having a knee and a foot member, comprising a shell adapted to receive therein the stump of a leg amputated below the knee, a stump support at the front or knee part of said shell, stump supports at the sides of said shell, a rear pivot support fixedly fastened to said shell, said supports being substantially circumferentially spaced on the interior of said shell, individual ball and socket connections between said shell and said front and side stump supports, adjustable links between said front stump support and said side stump supports, and adjustable links between said side stump supports and said rear support, said last links including balls which fit into ball sockets in said rear pivot support.

10. A socket for an artificial leg having a knee and a foot member, comprising a shell adapted to receive therein the stump of a leg amputated below the knee, a stump support at the front or knee part of said shell, stump supports at the sides of said shell, a rear support fixedly fastened to said shell, said supports being substantially circumferentially spaced on the interior of said shell, individual pivotal or swivel connections between said shell and said front and side stump supports, adjustable links interconnecting said supports, and an inner sleeve for said shell covering said links and having openings allowing said front and side stump supports to pass therethrough, said shell having openings at the locations of said links for enabling adjustment of said links from the outside of said shell.

11. A socket for an artificial limb, comprising a shell, a plurality of spaced stump supports arranged on the interior of said shell adapted to receive therein the stump of an amputated limb, individual ball and socket connections between said stump supports and said shell, and ball and socket links interconnecting said stump supports, said links being adjustable in length and comprising gear and rack constructions.

12. A socket for an artificial limb, comprising a shell, a plurality of non-overlapping substantially circumferentially spaced stump supports arranged on the interior of said shell and adapted to receive therein the stump of an amputated limb, individual swivel-type connections between said shell and stump supports, and links of adjustable length between said stump supports, and terminating thereat, said links having means inter-

mediate the ends thereof for adjusting the length independently of the other links.

13. A socket for an artificial limb, comprising a substantially annular shell, a plurality of circumferentially spaced stump supports arranged on the interior of said shell and fastened to said shell in pivotal relation thereto at locations adjacent said supports but intermediate the ends of said supports, and separate links pivotally interconnecting each stump support to the adjacent supports on opposite sides thereof, each of said links including means for adjusting the effective length thereof independently of the other links.

JOHN AHO.
